Charles E. Foster

UNITED STATES PATENT OFFICE.

WALTER HART, OF PHILADELPHIA, PENNSYLVANIA.

EGG-BEATER.

Specification of Letters Patent No. 31,663, dated March 12, 1861.

To all whom it may concern:

Be it known that I, WALTER HART, of Philadelphia, Pennsylvania, have invented a new and useful Improvement in Egg-
5 Beaters; and I do hereby declare the following to be a full, clear, and exact description of the same, reference being had to the accompanying drawing and to the letters of reference marked thereon.

10 My invention relates to an improvement in that class of egg beaters which consists of a screw spindle furnished with wire breakers or dashers, and operated by a reciprocating nut, and my improvement consists of a
15 tube with a screw thread, a nut, and wire beaters or dashers in combination with an internal rod having at the end a disk or button, the whole being constructed and arranged substantially as described hereafter
20 for the purpose of obviating certain defects experienced in this class of instruments, as hitherto constructed.

In order to enable others, to make and use my invention, I will now proceed to describe
25 its construction and operation.

On reference to the accompanying drawing, which forms a part of this specification, Figure 1 is an elevation, partly in section, of my improved egg beater. Fig. 2 a trans-
30 verse section on the line 1. 2 Fig. 1. Fig. 3 an inverted plan view. Fig. 4 a detached view of part of the instrument, and, Fig. 5 a modification of part of my improved beater.

35 Similar letters refer to similar parts throughout the several views.

B is a tube around which are coiled and secured in a spiral direction, any convenient number of wires C' C' (three being used in
40 the present instance) these wires forming the thread of a screw of which D is the nut, the latter consisting of a round or other suitably shaped piece of wood, or other material with a hole large enough to fit freely
45 over the tube and its wire threads, a pin a being screwed into this nut, and the point of this pin penetrating into the space between the spiral wires as seen in Fig. 2.

The wires are spread out and bent at their
50 lower ends so as to form the three breakers or dashers b b b all of which are firmly secured to the tube at the lower end of the same.

Through this tube B passes a rod G, which is secured at the top to the handle H and at the bottom to a short tube d, which forms a 55 part of the disk or button e. The length of the tube B is such, compared with the distance between the lower end of the handle H and the top of the short tube d, that the said tube B can have a slight longitudinal play 60 on the rod G.

In place of the spiral wires C, C, I in some instances lap around the tube spirally, a strip of metal as seen in Fig. 5 so as to form a spiral groove for receiving the point 65 of the set screw a. The eggs having been deposited in a suitable vessel the lower end of the above described instrument is placed in the vessel on the bottom of which the button e rests. The operator holding the 70 handle H in his right hand moves the nut D up and down with his left hand thereby imparting a rapid rotary motion first in one and then in the other direction to the tube and its beaters which rapidly reduce the 75 eggs to the desired consistency.

I am aware that an instrument composed of a screw spindle with breakers or dashers and operated by a reciprocating nut has been heretofore used for beating eggs, the screw 80 spindle however turned in the handle and at the point where it rested on the bottom of the vessel, in consequence of which two difficulties in the way of effectually using the instrument presented themselves. Firstly, 85 the instrument cannot be held steadily in its proper position owing to the constant turning of the point on the bottom of the vessel; secondly, a slight pressure on the handle induces so much friction as to interfere with the easy working of the instrument.

In my improved egg beater the base, consisting of the button e, which rests on the bottom of the vessel, is stationary and therefore has no tendency to slip and as the pressure imparted to it is sustained by the stationary rod and not by the tube the latter is free to rotate under any pressure to which the instrument may be necessarily subjected. 95 100

I do not desire to claim broadly an egg beater composed of wire dashers a screw threaded shaft and nut as such a device has been heretofore used but

I claim as my invention and desire to secure by Letters Patent—

The tube B, its screw thread, the nut D and beaters or dashers b in combination with the internal rod G and its disk or button e the whole being constructed and arranged substantially as and for the purpose herein set forth.

In testimony whereof, I have signed my name to this specification, in the presence of 10 two subscribing witnesses.

WALTER HART.
